GEORGE F. STEEDMAN, OF ST. LOUIS, MISSOURI, ASSIGNOR TO CURTIS & COMPANY MANUFACTURING COMPANY, OF WELLSTON, MISSOURI, A CORPORATION OF MISSOURI.

PACKING DEVICE.

1,000,563.

Specification of Letters Patent. Patented Aug. 15, 1911.

Application filed March 17, 1911. Serial No. 615,069.

To all whom it may concern:

Be it known that I, GEORGE F. STEEDMAN, a citizen of the United States, residing at St. Louis, Missouri, have invented a certain new and useful Improvement in Packing Devices, of which the following is a full, clear, and exact description, such as will enable others skilled in the art to which it appertains to make and use the same.

10 This invention relates to devices that are used for packing pistons, piston rods and other structures in which a flexible packing member is pressed against the contacting surface by the fluid pressure acting on the member to be packed.

15 The main object of my invention is to provide a device for the purpose described which will successfully pack a member whose surface is more or less irregular. 20 And another object is to provide an inexpensive pressure device that will press the flexible member against the surface to be packed when the fluid which the packing is intended to contain is under little or no pressure.

25 I have herein illustrated my invention embodied in devices that are used for packing pistons and piston rods but it will, of course, be understood that it could be used 30 for other purposes.

Figure 1 is a longitudinal sectional view of a cylinder provided with a piston that is equipped with a packing device constructed in accordance with my invention; Fig. 2 is a 35 cross sectional view taken on the line 2—2 of Fig. 1, the member which carries the pressure device being broken away so as to more clearly illustrate the construction of 40 said device; Fig. 3 is a sectional view of a device constructed in accordance with my invention for packing a piston rod; and Fig. 4 is a sectional view illustrating a slight modification of my invention.

45 Referring to Fig. 1 which illustrates one form of my invention, A designates a cylinder, and B designates a piston that is reciprocatingly mounted in said cylinder.

50 My improved packing device consists of a cup-shaped flexible member 1 which is provided with an integral ring-shaped flange 1^a that bears against the inner face of the cylinder, a pressure device carrier 2 connected to the piston and preferably arranged in such a manner that it clamps the 55 flexible cup-shaped member 1 to the piston,

and a pressure device 3 arranged between the carrier 2 and the flange 1^a on the flexible member 1 and operating to hold said flange tightly against the inner surface of the cylinder, the carrier 2 being provided in its 60 peripheral edge with a pocket or groove 2^a for receiving the pressure device 3. The carrier 2 can be connected to the piston in any suitable manner, as for example, by means of nuts 4 mounted on studs 5 that project 65 forwardly from the front face of the piston through openings in the carrier 2, and the front face of the carrier is preferably recessed, as shown in Fig. 1, so that the studs and nuts will not project beyond the carrier. 70

The pressure device 3 which I prefer to use consists of a coiled compression spring whose ends are preferably connected together, as shown in Fig. 2, so as to produce 75 a ring-shaped expanding device that is limber, pliable, resilient, flexible and elastic, and which constantly exerts outward pressure on the flange 1^a of the packing member 1. The means shown in Fig. 2 for connecting the ends of the spring 3 together consists of a short coiled spring 6 that is threaded into the coils of the spring 3 but any other suitable means could be used for this purpose. Furthermore, while I prefer 80 to use a coiled compression spring for pressing the packing member against the cylinder I do not wish it to be understood that my invention is limited to such a device for any other suitable means that is limber, 85 resilient and expansible could be used for this purpose. 90

The main advantage of a packing device of the construction above described is that the flexible flange 1^a of the packing member 95 conforms accurately to the surface against which it bears owing to the limberness, resiliency, and expansibility of the pressure device 3. Consequently, a packing device of this construction will produce a perfectly 100 tight joint between a piston and a cylinder whose inner surface is more or less irregular, as shown in Fig. 2.

Another desirable feature of such a packing device is that it can be manufactured at 105 a low cost; and still another feature that enhances its commercial value is the simple way of renewing the packing.

While I prefer to use leather or fibrous material for the packing member 1, said 110

member could be formed from certain kinds of metal, or successive layers of thin metal, which is soft and flexible enough to conform accurately to an uneven surface.

5 In Fig. 4 I have illustrated a structure wherein the packing member 10 is formed from thin layers of metal and provided with a flange 10^a whose outer edge is reduced in thickness so that it will be sufficiently flexible to conform accurately to the inner surface of the cylinder.

The packing device illustrated in Fig. 3 embodies all of the characteristics of the packing device previously described except that it is used for packing a piston rod C or other reciprocating device. The flexible packing member 20 is "hat-shaped" or provided with a ring-shaped flange 20^a through which the piston rod passes, and a ring-shaped pressure device 23, preferably a coiled tension spring, is arranged in such a manner that it exerts inward pressure on the flange 20^a and thus presses it tightly against the piston rod, said spring 23 being arranged 25 in a groove or pocket 22^a on a carrier 22 that secures the packing member to the stationary member D through which the piston rod passes. Heretofore, split rings formed from spring wire or bands of steel, have been used 30 for pressing a flexible packing member against the surface to be packed. If the surface being packed is perfectly true, such devices successfully perform their function, but if the surface is more or less irregular, a 35 leak will develop as soon as the fluid confined by the packing ceases to exert pressure on the packing member owing to the fact that a ring formed from wire or from a band or strip of metal is not limber or pliable and consequently cannot conform to the irregularities in the surface being 40 packed. I overcome this objectionable feature by using a pressure member which is not only resilient and elastic but also limber 45 and pliable, thereby producing a packing

device which will successfully pack an irregular surface even when the fluid which the packing device confines is under little or no pressure.

Having thus described my invention, what 50 I claim as new and desire to secure by Letters Patent is:

1. In a packing device, a packing member provided with a ring-shaped flange that is sufficiently flexible to conform to an irregular curved surface, a clamping member which retains said packing member in position, and a ring-shaped pressure device formed from a coiled compression spring and arranged in a pocket in said clamping member in engagement with the flange on the packing member. 55

2. A piston packing device consisting of a packing member mounted on a piston and provided with a ring-shaped flange, a clamping member for securing said packing member to the piston, said clamping member being provided with a groove, and a ring-shaped pressure device formed from a coiled compression spring and arranged in said 60 groove in engagement with the flange on said clamping member. 65

3. In a packing device, a packing member provided with a flexible ring-shaped flange, a clamping member that retains said packing member in position, said clamping member being provided with an annular pocket, a ring-shaped pressure device arranged in said pocket and consisting of a coiled compression spring, and a short coiled spring 70 threaded into the end portions of said compression spring for connecting the ends of said spring together. 75

In testimony whereof I hereunto affix my signature in the presence of two witnesses, 85 this 7th day of March, 1911.

GEORGE F. STEEDMAN.
